US00D905430S

(12) **United States Design Patent** (10) **Patent No.:** **US D905,430 S**
(45) **Date of Patent:** **** Dec. 22, 2020**

(54) **CASE FOR EARPHONES**

(71) Applicant: **SPIGEN KOREA CO., LTD.**, Seoul (KR)

(72) Inventors: **Jung Hun Kwak**, Seoul (KR); **Eun Hee Koo**, Seoul (KR)

(73) Assignee: **SPIGEN KOREA CO., LTD.**, Seoul (KR)

(**) Term: **15 Years**

(21) Appl. No.: **29/714,902**

(22) Filed: **Nov. 26, 2019**

(51) LOC (12) Cl. **03-01**

(52) U.S. Cl.

USPC **D3/273**

(58) **Field of Classification Search**

USPC D3/201, 203.1, 204, 205, 207–208, 212, D3/215, 218, 269, 273–274, 276, 283, D3/284, 294–300, 302, 303, 315, 901, D3/903; D9/414, 418, 420, 430, 432; D28/66, 73, 76, 78, 91; D14/188, 201, D14/204, 205, 209.1, 217, 250, 251, 440, D14/447

(57) **CLAIM**

The ornamental design for a case for earphones, as shown and described.

DESCRIPTION

FIG. 1 is a front perspective view of a case for earphones showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded front perspective view of the case showing the components separated for clarity of disclosure. The oblique shade lines throughout the figures show transparency or translucency. The broken lines throughout the drawing figures depict portions of the case for earphones that form no part of the claimed design.

1 Claim, 9 Drawing Sheets
